UNITED STATES PATENT OFFICE.

GEORGE A. SCHUH AND ALFRED E. SCHUH, OF BUFFALO, NEW YORK.

DESIGN FOR A COMBINED LICENSE-PLATE HOLDER, NAME PLATE, AND SIGNAL LIGHT.

Application filed September 1, 1925. Serial No. 14,683. Term of patent 14 years.

To all whom it may concern:

Be it known that we, GEORGE A. SCHUH and ALFRED E. SCHUH, citizens of the United States, residing at Buffalo, in the county of Erie and State of New York, have invented a new, original, and ornamental Design for Combined License-Plate Holder, Name Plate, and Signal Light, of which the following is a specification, reference being had to the accompanying drawing, forming a part thereof.

In the accompanying drawings:

The accompanying drawing shows a perspective view of a combined license plate holder, name plate and signal light embodying our new design.

We claim:

The ornamental design of a combined license plate holder, name plate and signal light, as shown.

GEORGE A. SCHUH.
ALFRED E. SCHUH.
